UNITED STATES PATENT OFFICE.

JUDSON C. PEWTHER, OF DENVER, COLORADO.

FOLDING TABLE.

1,379,284.

Specification of Letters Patent. Patented May 24, 1921.

Application filed September 15, 1920. Serial No. 410,507.

To all whom it may concern:

Be it known that I, JUDSON C. PEWTHER, a citizen of the United States, residing at Denver, in the county of Denver, and State 5 of Colorado, have invented certain new and useful Improvements in Folding Tables, of which the following is a specification, reference being had to the accompanying drawings.

10 This invention relates to certain improvements in folding tables, and it is an object of the invention to provide a novel and improved device of this general character which, when folded or compacted, can be 15 used to advantage as a receptacle or case.

It is also an object of the invention to provide a novel and improved device of this general character embodying two substantially duplicate sections connected for relative swinging movement which, when folded, provide a receptacle or case and which, when extended, constitute a table top, together with supporting legs operatively engaged with each of the sections and which legs are 25 readily foldable within the sections, said legs, when so folded, occupying a minimum of space.

An additional object of the invention is to provide a novel and improved structure of 30 this general character embodying swinging legs which, when extended, are effectively held or braced in such position.

Another object of the invention is to provide a novel and improved device of this 35 general character embodying swinging legs foldable with respect to the sections comprised within the body of the device, together with means whereby said legs, when in folded position, are held against outward 40 or extended movement.

The invention consists in the details of construction and in the combination and arrangement of the several parts of my improved folding table whereby certain important advantages are attained and the device rendered simpler, less expensive and otherwise more convenient and advantageous for use, as will be hereinafter more fully set forth.

50 The novel features of my invention will hereinafter be definitely claimed.

In order that my invention may be the better understood, I will now proceed to describe the same with reference to the accompanying drawings, wherein:

Figure 1 is a view in perspective of a

folding table constructed in accordance with an embodiment of my invention and in compacted form for use as a receptacle or case.

Fig. 2 is a view in bottom plan of the device as herein disclosed with the sections in open position and the supporting legs folded therein.

Fig. 3 is a view in bottom plan of my improved device with the sections in open 65 position and the legs extended.

Fig. 4 is a view in side elevation, with portions broken away, of my improved device in extended position for use as a table, and

70 Fig. 5 is a fragmentary view in perspective illustrating in detail the means herein employed for holding the legs against outward movement when in folded position with respect to its coacting section.

75 My improved device as herein disclosed comprises two substantially duplicate sections A. Each of the sections A includes a flat body portion 1 of requisite diameter and preferably oblong with its marginal portion defined by the inwardly directed flanges 2. A pair of adjacent longitudinal flanges 2 have their free margins hingedly connected one with the other, as at 3, whereby the sections A are capable of relative 80 swinging movement, said hingedly connected flanges 2 abutting when the sections A are separated, whereby the body portions 1 of both of the sections provide a substantially flat top particularly adapted for use as a 85 table.

90 When the sections A are at the limit of their outward swinging movement, the same are held against accidental inward movement through the medium of the substantially U-shaped clip 4 adapted to straddle the hingedly connected flanges 2 and which clip is carried by an end portion of an elongated resilient arm 5 having its opposite end portion pivotally engaged, as at 6, with 95 the inner wall of the hingedly connected flange 2 of one of the sections A. The arm 5 is resilient in order to permit the clip 4, when disengaged from the abutting flanges 2, to be positioned within one of the sections A, as indicated in Fig. 2, so that said sections may be swung inwardly into closed 100 position.

105 Each of the body portions 1 has secured to the inner face thereof at its corners and to the adjacent end flanges 2 the angular brackets 7 each of which is provided at a

point in close proximity to the adjacent body portion 1 with a bearing 8 extending in a direction transversely of the body portion 1.

- 5 Coacting with each end of a section A is a supporting leg L preferably formed of a wire strand of requisite gage and possessing the necessary stiffness. The leg L closely simulates a V and the free end portions thereof are provided with the inturned angular extremities 9 which extend within a pair of transversely alined bearings 8. It is to be particularly noted that the extremities 9 extend within the bearings 8 through 10 the ends thereof in close proximity to the adjacent longitudinal flanges 2 whereby accidental displacement of the leg L with respect to the bearings 8 is substantially eliminated.

The apex portion 10 of each of the legs L 20 is substantially straight and disposed in a direction transversely to the coacting sections A. Encircling the straight portion 10 is a coiled sleeve 11 extending laterally from an end portion of a brace rod 12 and integrally formed therewith. The rod 12 is of desired length and is provided at its opposite end portion with an angularly directed extension 14 which engages through an opening 15 formed in an inwardly directed 25 portion 16 of a plate 17 suitably anchored to an outer longitudinal flange 2 of a section A. The angular extension 14 is disposed through the opening 15 of the coacting portion 16 when the leg L is extended into 30 working or supporting position and wherein the rod 12 holds said leg against inward swinging movement.

When the device is to be folded or compacted, the legs L of each of the sections A 40 readily swing inwardly thereof and are positioned in close proximity to the body portion 1. As the leg L swings inwardly of its coacting section A, the outer strand 18 of said leg springs by the portion or wing 16 45 of the plate 17. When the legs L are at the limit of their inward or folding movement, the portion or wing 16 overlies said outer strand 18 and thereby provides stops to normally hold said legs against outward swinging movement, so that said legs will offer 50 no undue obstruction to the interior of the section A.

To facilitate the passage of the outer strand 18 of each of the legs L past its coacting portion or wing 16, the same is provided with the upper and lower cam edges a and b. The desired passage of the strand 18 beyond the wing or portion 16 is facilitated by the inherent resiliency possessed by 60 the strand 18.

The sections A are maintained or held in their folded relation by a catch 19 pivotally engaged with the outer longitudinal flange of one of the sections A and coacting with 65 the headed stud or keeper 20 carried by the

adjacent flange 2 of the second section A. This flange 2 of the second section is also provided with the hand hold or grasp 21 preferably flexible whereby the device may be readily transported when in its folded or compacted adjustment.

The brackets 7 carried by one of the sections A extend outwardly beyond the adjacent flanges 2 so that when the sections A are compacted or folded, said extended portions of these brackets 7 will overlap the inner faces of the end flanges 2 of the second section A, whereby the maintenance of said sections A in their closed or folded relation is materially facilitated.

From the foregoing description it is thought to be obvious that a folding table constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A device of the character described comprising substantially duplicate sections, each of said sections embodying a flat body member having its marginal portion defined by inwardly directed flanges, the free marginal portions of adjacent flanges of the sections being hingedly connected whereby said sections may be folded into closed relation or extended to bring the body portions into substantially coplanar relation, a supporting leg operatively engaged with each end portion of each of the sections, said supporting leg being substantially V-shaped in form with its extremities angularly disposed, bearings carried by the coacting section to receive said angular extremities whereby the leg is capable of swinging movement with respect to the section, a brace member having one end portion pivotally engaged with the apex portion of the leg, and a wing extending inwardly from an outer flange of the coacting section, the free end portion of the brace member and the wing being provided with coacting means whereby the same may be connected one to the other.

2. A device of the character described comprising substantially duplicate sections, each of said sections embodying a flat body member having its marginal portion defined by inwardly directed flanges, the free marginal portions of adjacent flanges of the sections being hingedly connected whereby said sections may be folded into closed re-

lation or extended to bring the body portions into substantially coplanar relation, a supporting leg operatively engaged with each end portion of each of the sections, 5 said supporting leg being substantially V-shaped in form, the section and extremities of the leg being provided with coacting means whereby the leg is capable of swinging movement with respect to the section, 10 and a brace member having one end portion pivotally engaged with the apex portion of the leg, the opposite end portions of the brace member and the section being provided with coacting means whereby the 15 same may be connected one to the other.

3. A device of the character described comprising two hingedly connected sections foldable into closed relation or extended to bring the sections substantially into coplanar relation, a supporting leg operatively engaged with each end portion of each of the sections, said supporting leg being substantially V-shaped in form and having swinging movement with respect to the section, 20 a brace member having one end portion pivotally engaged with the apex portion of the leg comprising a sleeve carried by the brace member and loosely surrounding the apex portion of the leg. 25

the leg, and coacting means carried by the brace member and the section whereby the same may be connected one to the other.

4. A device of the character described 30 comprising two hingedly connected sections foldable into closed relation or extended to bring the sections substantially into coplanar relation, a supporting leg operatively engaged with each end portion of each of the sections, said supporting leg being substantially V-shaped in form and having swinging movement with respect to the section, 35 a brace member having one end portion pivotally engaged with the apex portion of the leg, and coacting means carried by the brace member and the section whereby the same may be connected one to the other, the pivotal connection between the brace member and the apex portion of the 40 leg comprising a sleeve carried by the brace member and loosely surrounding the apex portion of the leg.

In testimony whereof I hereunto affix my signature.

JUDSON C. PEWTER.
